(57) CLAIM

The ornamental design for an electric iron, as shown.

DESCRIPTION

FIG. 1 is a perspective view of the electric iron of the present invention;

FIG. 2 is a bottom view of the electric iron of the present invention;

FIG. 3 is a side view of the electric iron of the present invention;

FIG. 4 is a top view of the electric iron of the present invention;

FIG. 5 is a front view of the electric iron of the present invention;

FIG. 6 is a rear view of the electric iron of the present invention;

FIG. 7 is a perspective view of a second embodiment of the electric iron of the present invention;

FIG. 8 is a top view of the second embodiment of the electric iron of the present invention;

FIG. 9 is a side view of the second embodiment of the electric iron of the present invention;

FIG. 10 is a bottom view of a second embodiment of the electric iron of the present invention;

FIG. 11 is a front view of a second embodiment of the electric iron of the present invention; and,

FIG. 12 is a rear view of a second embodiment of the electric iron of the present invention.
